UNITED STATES PATENT OFFICE.

WILHELM TROELLER, OF FRANKFORT-ON-THE-MAIN, GERMANY.

FURNACE.

1,207,819.

Specification of Letters Patent. Patented Dec. 12, 1916.

Application filed April 9, 1915. Serial No. 20,163.

To all whom it may concern:

Be it known that I, WILHELM TROELLER, a subject of the Emperor of Germany, residing at Frankfort-on-the-Main, Germany, have invented certain new and useful Improvements in Furnaces, of which the following is a specification.

The invention relates to improvements in furnaces for sintering, burning, roasting, reducing, or otherwise treating bricks, ores, cement materials or other substances.

The furnace forming the subject-matter of the invention consists of a plurality of iron receivers into which the material is charged in such a manner as to leave passages for the gases. Between each two receivers there is inserted a compartment, to which the flames and gases intended for the treatment of the charge are admitted and from which the waste gases are discharged. The receivers located between each two of these compartments are arranged in such a manner that they can be removed from the furnace independent of the other receivers and of the compartments, after the treatment of the charge is completed and that a new receiver may be inserted between each two compartments without removing any of the other receivers or the compartments from their position. Each of the compartments is in connection with an admission and a discharge conduit for the different gases draining into corresponding main channels, so that each of these compartments can be connected to or shut off from these main channels. The working of the furnace thus constructed is such that the several receivers arranged one behind the other one will be in different stages of treatment, the recently inserted receiver being in an initial stage of the treatment, whereas the receiver which was subjected to treatment during the longest time is undergoing the most intense treatment or is in a stage of subsequent treatment. When sintering of ore, cement materials or the like, is to be accomplished, then the receiver being in the furnace for the longest time will be nearest to the compartment wherein the heating flame is generated, or it will be exposed in front of the compartment, in which the heating flame is generated, to subsequent treatment by means of air or other gases with a view to cooling or producing chemical reactions.

55 The compartments and receivers will be preferably arranged one behind the other

according to a recurvant line, the operation thus progressing always upon this line. Between the compartment wherein the operation is at its last stage and the compartment, wherein the operation is at the beginning, there is left a free space of the length of one receiver. After the removal of a receiver, the treatment of which is finished, a receiver with fresh material is inserted into said free space.

The drawing shows a furnace according to the invention, Figures 1 and 2 being respectively plans in two different working stages, Fig. 3 a longitudinal section according to line A—B of Fig. 1, and Fig. 4 a cross-section after C—D of Fig. 1.

The receivers *a* (for instance six in number, designated *a*¹ to *a*⁶) which may be formed of several sections connected together, as shown in the drawings, are charged with the material to be treated in such a manner as to leave gas passages. They are removable transversely of the longitudinal axis of the furnace, upon rails (or otherwise, for instance by means of a hoisting device or the like) and inserted between each two of the free compartments *b* (*b*¹ to *b*⁶) intended to be used successively as burner chambers, air admission chambers, and waste gas chambers. Each of these compartments *b*¹ to *b*⁶ is connected by means of branch pipes *c* to the main gas conduit *d*, by means of branch pipes *e* to the main air channel *f* and by means of branch pipes *g* to the flue channel *h*. Said branch pipes *c*, *e*, *g* are provided with slide-valves by means of which the free compartments *b* can, according to the requirements of the working stage, either be connected with the conduits *d*, *f*, *h* or shut off from them. As shown in the drawings, also the free compartments *b*¹ to *b*⁶ may be arranged on rails and be removed transversely of the longitudinal axis of the furnace, so as to enable their easy replacement in case of wear. During the working of the furnace however these compartments are always in fixed connection with the conduits.

The furnace plant is arranged in a recurvant line in such a manner that a free space of the length of one receiver is left between the last compartment *b*⁶ connected to the flue channel and the first one *b*¹ connected to the air admission. In the rectangular furnace arrangement shown in the drawing, the connection of the two parallel lines upon which are arranged the com-

partments and receivers is secured by means of the connecting compartments V^1 V^2 mounted on wheels and removable upon rails.

- 5 The operation of the furnace may be as follows: In the position shown in Fig. 1, air is admitted to the compartment b^1 which flows through receiver a^1 and combines in the compartment b^2 with the gas there admitted, forming a flame which first propagates through the receiver a^2 , then across the connecting compartment V^1 , receivers and compartments a^3 , b^3 , a^4 , b^4 , a^5 , b^5 , and the connecting compartment V^2 to the compartment b^6 , the latter communicating with the flue channel. After the receiver a^1 is sufficiently cooled and heating is accomplished in the receiver a^2 , the slide valves of the air conduit e connected to b^1 and of the gas conduit c connected to b^2 are closed, the receiver with finished treatment a^1 is disengaged from the compartments b^1 and b^2 and removed sidewise for being discharged and filled again. The front covers i are removed from the compartments b^6 and b^1 and a new receiver a^6 filled with fresh material is inserted between b^6 and b^1 . The right hand front opening of the compartment b^1 as well as the left hand front opening of compartment b^2 are then provided with covers i ; by opening the slide-valves in the corresponding conduits c , e , g , communication is established between compartment b^2 and air conduit f , compartment b^3 with gas conduit d and compartment b^1 with flue channel h . Working is thus advanced in the furnace by one receiver. The same manipulation is repeated each time after treatment is finished in the receiver newly under treatment.

Fig. 2 shows the condition of the apparatus after the material in each of the receivers shown in Fig. 1 has been treated and each of the receivers has been removed. In this case the air flows through receiver a^6 and the flame generated in compartment b^1 flows successively through the other receivers. As the compartment V^2 is not in use, it may be removed if desired as indicated in dotted lines.

The furnace may of course be composed of a more or less great number of receivers and compartments, as shown in the drawing, and the furnace arrangement may be given another form. For instance the receivers and compartments might be disposed in the form of a square, polygon or circle. In the case of rectangular arrangement the connecting compartments V^1 V^2 , may be dispensed with, by inserting at the narrow sides of the rectangle still one or more receivers and by providing fixed corner-piece compartments at the angles, acting in the same way as the other compartments b . The whole furnace might also be arranged in a

straight line, treatment thus proceeding along this line, at the ends of which the receivers containing material still under treatment have to be interchanged in such a way that working can proceed in the inverted direction.

The furnace may serve different purposes and can be worked otherwise than described. For instance the subsequent treatment with air may be replaced by subsequent treatment with other, for instance reducing gases, or subsequent treatment may be dispensed with at all. Instead of treating with a heating flame, hot reducing gases might be used for reducing the material or for bringing about other reactions. Oil or other liquid or solid fuel may also be employed for producing the heating flame instead of burning gas. The invention may be applied for carrying through different metallurgical or chemical methods of treatment. The operation may be carried through in such a way that the heat required for sintering or other treatment is produced by combustion of the gases within the very material to be treated (by flameless combustion).

What I claim is:

1. In a furnace for the purpose described, in combination, two compartments, one of the compartments being provided with a fluid inlet and the other of the compartments being provided with a fluid outlet, and a removable receiver for the material to be treated inserted between the compartments and communicating therewith, said receiver being removable without moving the compartments.

2. In a furnace for the purpose described, in combination, a plurality of compartments arranged in line, means associated with each compartment for the admission and discharge of fluid, and a plurality of receivers for the material to be treated arranged in line in alternating relation with the compartments and communicating therewith and removable transversely of the line.

3. In a furnace for the purpose described, in combination, a plurality of compartments arranged in series, means associated with each compartment for the admission and discharge of fluid, a plurality of removable receivers for the material to be treated arranged in alternating relation between the compartments and communicating therewith, and guiding means for two receivers whereby the two receivers may be simultaneously removed from the furnace along separate non-parallel paths.

4. In a furnace for the purpose described, in combination, a plurality of compartments arranged in series, means associated with each compartment for the admission and discharge of fluid, and a plurality of removable receivers for the material to be treated

arranged in series in alternating relation with the compartments and communicating therewith, each receiver being removable without moving any other receiver or any of the 5 compartments.

5. In a furnace for the purpose described, in combination, two rows of compartments, means associated with each compartment for the admission and discharge of fluid, removable 10 receivers for the material to be treated arranged between the compartments of each row, and fluid conducting means connecting the compartments at each end of one row with the compartments at the corresponding 15 end of the other row.

6. In a furnace for the purpose described, in combination, a plurality of ore and fluid receiving compartments arranged in line alternately to form longitudinal subdivisions 20 of the furnace, a plurality of the ore compartments being separately removable from the furnace transversely of the furnace, and permanently connected conduits one for directly discharging fluid into one of the fluid 25 receiving compartments and the other for directly discharging fluid from another fluid receiving compartment.

7. In a furnace for the purpose described, in combination, a plurality of ore and fluid receiving compartments arranged in line 30 alternately to form longitudinal subdivisions of the furnace, a plurality of the ore compartments being separately removable from the furnace transversely of the furnace, and means for directly discharging fluid selectively 35 into either one of two fluid receiving compartments without moving such compartments.

8. In a furnace for the purpose described, in combination, a plurality of ore and fluid 40 receiving compartments arranged in line alternately to form longitudinal subdivisions of the furnace, and means for directly feeding fluid to one of two fluid receiving compartments, at least three of the ore compartments 45 being removable from the furnace simultaneously.

In testimony whereof I affix my signature in presence of two witnesses.

WILHELM TROELLER.
